UNITED STATES PATENT OFFICE.

HENRY PETER CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE.

1,262,639.

Specification of Letters Patent. Patented Apr. 16, 1918.

Application filed September 14, 1917. Serial No. 191,372.

To all whom it may concern:

Be it known that I, HENRY P. CLAUSEN, a citizen of the United States, residing at Mount Vernon, in the county of Westchester 5 and State of New York, have invented certain new and useful Improvements in Telephone-Exchanges, of which the following is a full, clear, concise, and exact description.

This invention relates to telephone exchanges and more particularly to the arrangement of substation circuits in connection with which impulse sending devices are used for transmitting impulses over the subscriber's line to cause the selective actuation of the central office switching mechanism.

As a precaution against the improper operation of the selective switches, substation circuits have heretofore been arranged so 20 that a subscriber in initiating a call causes a closure of the line circuit by the first movement of the impulse transmitter from its normal position. Since, by such a provision the completion of the line circuit to 25 start the finder or equivalent switch does not depend upon the removal of the receiver from its switchhook, a sufficient period of time is insured for said switch to perform its complete operation before the first series 30 of impulses is transmitted. This of course is an advantageous feature where the normal operating conditions are considered. However, the placing of the subscriber's line circuit under the control of the calling de- 35 vice independently of the receiver switchhook gives rise to the possibility of certain undesirable conditions. If, for example, the subscriber's calling devices is inadvertently actuated, a finder or equivalent switch 40 moves into connection with the line and extends the same to a succeeding selective switch. Then when impulses are subsequently sent over the line said selective switch is actuated to seize an idle trunk 45 and render the same busy to other switches until the calling device is again restored to its normal position.

The object of the present invention is to 50 provide a substation circuit arrangement of the above character, wherein the first movement of the impulse sender from its normal position establishes a closure of the line circuit independently of the switchhook position, and also to provide means whereby

the return or line interrupting movement of 55 the sender is only effective to transmit impulses over the line when said switchhook is released by the removal of the receiver.

A more thorough comprehension of the invention will be had from a study of the 60 following description, taken in conjunction with the accompanying drawing.

In the drawing, Figure 1 diagrammatically illustrates the circuits and mechanism of a subscriber's substation embodying the 65 features of the said invention, and Fig. 2 shows an alternative arrangement of the circuits and devices illustrated in Fig. 1.

Referring to Fig. 1 the dial of a calling transmitter is represented at 1, and is provided with a series of finger-holds 2 by means of which the transmitter is manipulated to transmit any desired number of impulses over the line conductors 3 and 4. An impulse wheel 5 has a series of circuit 75 interrupting teeth 6 arranged to coöperate with the lever 7, and is also provided with a finger 8. Finger 8 is arranged to retain the off-normal contacts 9 and 10 open while the dial 1 is in its normal inoperative position, but upon the first movement of said dial permits the contacts 9 and 10 to close for a purpose later to be described.

Assume that the subscriber in initiating a call removes his receiver 11 from the switchhook 12 before he commences to operate the dial 1. A circuit is thereby closed for line conductors 3 and 4 as follows: conductor 3, receiver 11, transmitter 13, contact 14, contact lever 15, interrupting contacts 16 and 17, to line conductor 4. The closure of this circuit sets a line finder in operation in the well known manner to extend said line to an idle selector. The subscriber now rotates the dial 1 in a clockwise direction through the proper distance. When released the impulse wheel 5, returning to normal under the influence of spring 18, causes teeth 6 to engage lever 7, thereby opening and closing the interrupter springs 100 16 and 17 a number of times corresponding to the particular setting of the dial 1. Should, however, the subscriber fail to remove his receiver from the hook to complete the above traced circuit until after the dial 105 1 has been partially rotated to its set position, another circuit will be closed between conductors 3 and 4 to give the line finder suffi-

cient time in which to complete its operation. Such circuit is completed at the off-normal contacts 9 and 10 at the first rotation of the dial, and may be traced from 5 conductor 3, conductor 19, contacts 10 and 9, contacts 20 and 21, conductor 22, to conductor 4. The subscriber having, as assumed, removed his receiver 11 before the sender reaches its full forward position, said 10 sender upon its return to normal interrupts the line circuit as already described.

It will be observed that the previously traced bridge across line 3, 4 comprising conductor 19, contacts 10, 9, contacts 20, 21 15 and conductor 22 does not include the interrupter contacts 16, 17. When receiver 11 is removed from the hook 12, this bridge is opened by contact lever 15 pressing contact 20 out of engagement with contact 21, and 20 a new bridge is closed by the engagement of contacts 15 and 20 to include the interrupter contacts 16 and 17 in the circuit of the line. This latter circuit is traceable from conductor 3, conductor 19, contacts 10 and 9, contacts 20 and 15, interrupter contacts 16 and 17, to conductor 4.

While the sender is returning to normal the successive interruptions by contacts 16 and 17 do not produce a disagreeable click 30 in the receiver since the same is shunted out by the circuit just traced. Upon the return of dial 1 to its normal position, finger 8 again moves contact 9 out of engagement with contact 10.

35 Assume now that the subscriber, with no intention of initiating a call, accidentally operates the calling dial 1. As above explained this will result in the operation of a finder or other preliminary switch. But in 40 this case, since the receiver 11 remains on the hook 12, the opening and closing of interrupter contacts 16 and 17 by the return movement of the sender is not effective to send impulses over the line.

45 Referring to Fig. 2, the removal of receiver 11, from switchhook 12 closes a circuit for the line as follows: line conductor 3, receiver 11, transmitter 13, contact 14, switchhook 12 interrupter contacts 16 and 50 17, to line conductor 4. If the receiver is left on its hook and the dial 1 is operated, the first movement thereof from its normal position closes a circuit for the subscriber's line, traceable as follows: conductors 3 and 55 19, off-normal contacts 10 and 9, switchhook 12, contact 23, conductor 24, to line conductor 4. It will be seen that this bridge across conductors 3 and 4, as in the case of Fig. 1, does not include the interrupting contacts 60 16 and 17, and therefore, the return rotation of dial 1, while effective to open and close said contacts, does not result in the transmission of impulses over the line. When, however, receiver 11 is removed from hook

12, the above traced bridge is opened at contact 23. In this case the operation of interrupter contacts 16 and 17 by the return of dial 1 causes a series of impulses to be sent over the line circuit. This circuit is traceable as follows: conductors 3 and 19, 65 off-normal contacts 10 and 9, interrupter contacts 16 and 17, to conductor 4. 70

What is claimed is:

1. A telephone substation having in combination, a subscriber's line, a switchhook, 75 a sending device operative to successively interrupt said line, means for closing said line by the first movement of said device from its normal position, and means controlled by the switchhook for maintaining said line 80 closed during the operation of the sending device.

2. A telephone substation having in combination, a normally open line circuit, a switchhook, a sending device arranged to 85 successively interrupt said line circuit, contacts operated by said sending device when moved from its normal position for closing said circuit, and means controlled by said switchhook for rendering the operation of 90 said sending device ineffective.

3. A telephone substation having in combination, a line, a sending device, a switchhook, a circuit including said line in series, means arranged to close said circuit when 95 said device is moved from its normal position, a second circuit including said line in series, interrupter contacts therein arranged to be operated by said sending device, and means controlled by said switchhook for rendering effective either of said circuits. 100

4. A telephone substation having in combination, a line, a switchhook, a sending device, a set of contacts arranged to be closed by the movement of said device from its normal position, a set of interrupter contacts arranged to be actuated by the return movement of said device, and means controlled by the switchhook for connecting said line in series with either of said sets of contacts. 105

5. A telephone substation having in combination, a line, a movable switchhook, a sending device, a set of off-normal contacts closed by the first movement of said device, a set of interrupter contacts arranged to be 110 actuated by the return movement of said device, and means for closing said line in series with said off-normal contacts while the switchhook is in one position and for closing said line in series with both of said sets of 115 contacts while the switchhook is in another position.

6. A telephone substation having in combination, a line, a receiver and its switchhook associated with said line, a sending device, contacts actuated thereby for interrupting said line, a normally open bridge across said line arranged in shunt relation to the 125

interrupter contacts, off-normal contacts in said bridge for closing the same when said device is moved from its normal position, and means controlled by said switchhook for 5 altering said bridge from shunt to series relation to said interrupter contacts, said bridge also serving to shunt the receiver during the operation of said sending device. In witness whereof, I hereunto subscribe my name this 8th day of September A. D., 1917.

HENRY PETER CLAUSEN.
